INTERNAL COMBUSTION ENGINE

Charles Brebeck, Herkimer, N. Y.

Application April 18, 1938, Serial No. 202,725

5 Claims. (Cl. 123—73)

This invention pertains to internal combustion engines and more particularly to engines of the two cycle type.

In any internal combustion engine cylinder, injurious temperature stresses may be caused by injudicious distribution of metal, particularly at the valve ports. Unequal distribution of metal also causes non-uniform radial expansion of the cylinder bore, which frequently results in abrasion of the cylinder walls and piston, giving rise to leakage between them and resulting in loss of compression and power. These effects are particularly damaging to miniature engines such as are used in toy airplanes, toy boats, etc. Even the slightest distortion of the cylinder affects such an engine seriously, making starting difficult and causing impairment of operating efficiency. For these reasons it is important, in the case of small one-piece cylinders to produce a symmetrical design, at least as far as the combustion chamber and the adjacent parts are concerned.

It has been customary among miniature engine designers to follow designs of larger engines. In these designs the cylinders are secured at their lower ends to the crank cases. Ports and transfer passages are formed in members either cast, welded, brazed, soldered, or clamped onto the cylinder barrel. These methods of forming ports and passages set up stresses which cause cylinder distortion and unevenness of wall thickness.

The use of cast iron for small engines is unsatisfactory because of casting difficulties. The location of a portion of the firing chamber within the crank case may result in undesirably high crank case temperatures, and in localized hot spots which cause cylinder and crank case distortion. Where aluminum or aluminum alloy crank cases are used with iron or steel cylinders the unequal rates of expansion of the two metals may cause separation between the cylinder and crank case. This may result in exhaust gases entering the crank case and causing an explosion, or in gas charges seeping out of the exhaust port, and in any event invites corrosion of the metals where they overlap. The parts may even be corroded in such a way as to cause seizure between the cylinder and crank case, and to prevent disassembly without breakage, especially where, as in miniature engines, the metal sections are thin.

I have found after intensive study of the subject that for the above reasons practices followed in making large engines cannot be followed in making miniature engines, and hence that factors which were relatively unimportant in large engines become highly important in miniature de-

signs, and constitute the difference between success and failure in making engines of the latter type.

Accordingly the main object of my invention is to produce an internal combustion engine in which the heat transfer surfaces are symmetrically arranged; in which maximum strength of parts may be obtained in parts of small section, and to generally modify and improve the structure and operation of engines of the two-cycle type.

Other objects and advantages will appear from the following specification when read in connection with the accompanying drawing in which:

Figure 1 is a vertical axial section of one form of internal combustion engine embodying the present invention; and

Figure 2 is a section on line 2—2 of Fig. 1 illustrating the heat transfer conditions as they are approximated in engines embodying the invention.

In the drawing, 1 represents the cylinder, which is preferably manufactured by machining from a solid bar of steel. This method of manufacture makes it possible to produce a cylinder wall of thin uniform section throughout, and to obtain symmetry and strength which cannot be attained with cast metal, particularly where the parts are small. Fins 3 are formed on the cylinder to aid in dissipating heat therefrom to the surrounding air, and a tapped hole 4 is provided for a spark plug (not shown). From the lower half of the cylinder and integral with it extends a peripheral mounting flange 5, which is in a plane perpendicular to the axis of the cylinder 1.

I locate the exhaust port 6 above the flange 5, and hence, above the top of the crank case extension so that exhaust gases do not come into contact with the crank case as they do in other engines of similar design. This exhaust port, being in the part of the cylinder outside the crank case extension, is in close proximity to the cooling fins 3. Hence the heat of the exhaust gases spreads rapidly and is dissipated so that local distortion of the cylinder at the exhaust port is minimized. By having the exhaust port above the mounting flange 5, the firing chamber is separated entirely from the crank case and an explosion in the crank case caused by seepage of exhaust gases into it is made impossible. By having the exhaust port 6 above the mounting flange 5 and, therefore, the firing chamber entirely above the flange, a greater portion of the cylinder is external to the crank case. Hence,

I am enabled to have more space covered by cooling fins 3 on the cylinder than can be covered on a cylinder of the same size where the exhaust port is below the mounting flange.

5 The mounting flange 5 may be ground to fit closely on the upper surface of an extension of the crank case 8 or, as shown in the drawing, such surfaces may have interposed between them a gasket 15 of suitable material, such as asbestos, 10 copper, or the like. The crank case 8 is preferably made of aluminum or aluminum alloy so that it will be of minimum weight. The cylinder 1 fits within the extension of the crank case so that intake port 11 is opposite crank case intake 15 passage 7, and transfer port 9 connects with channel 10 in the crank case. Transfer port 9 is formed of openings in the wall of the cylinder and grooves in the under side of flange 5, the bottom of the grooves being above the lower edge 20 of said flange and below the top edge of said flange. The plane passing through the top of the flange is, therefore, above the transfer port and below the exhaust port. This brings the tops of the transfer ports 9 and the bottoms of 25 the exhaust ports 6 into very close relationship axially (Fig. 1), so that the baffle 14 carried by the head of piston 12 can be made of a minimum height for most efficient operation.

This relation of the ports 6 and 9 makes it 30 possible to produce, if desired, both a transfer port and an exhaust port by a single drilling, or equivalent, operation and at the same time gives the transfer ports the upward inclination indicated in Figs. 1 and 2. This inclination functions 35 to direct the entering gases upwardly into the combustion chamber, thus promoting turbulence in the charge and assisting in the rapid and thorough expulsion of the exhaust gases. The piston 12 carries the usual piston rings 13.

40 In attaching the cylinder 1 to the crank case 8, the only securing means necessary are cap-screws which are passed through holes 16 in the mounting flange 5 and into recesses tapped in the crank case. No clamps, lugs, or other projections are used or are necessary, and since 45 there are no ports formed in parts attached to the cylinder, each port being merely a plurality of holes in the cylinder wall, the mass of metal of the cylinder is evenly distributed and no distortion is caused by hot spots.

50 In a miniature light weight engine, the lateral thrust of the piston may be sufficient to bend the cylinder slightly, and thus to lead to breakage. When, e. g., the crank 17 is horizontal, the lateral thrust of the piston 12 will be greatest. As 55 shown in dotted lines in Figure 1, when the crank is horizontal, the piston is in such a position that its wrist pin 18 will be in substantial alignment with the mounting flange 5. The cylinder is 60 thus strengthened, and indeed supported, at the point of its maximum lateral stress.

Referring to Figure 2, I shall now describe the effect of heat on the expansion of the metal of the improved cylinder. When a mass of metal 65 in a particular portion of a cylinder is heated, it expands a definite amount. Unless this expansion is counteracted by an equal expansion of the metal in the area opposite, distortion of the cylinder results. In order that expansion on opposite 70 sides of the cylinder may be the same, it is necessary that the masses of metal in all opposite areas be the same. It is plainly evident that in this cylinder the mass of metal indicated by arrow *a* is equal to that at *a'*, and similarly *b* 75 and *b'*, and *c* and *c'* represent respectively equal

and opposite cylinder masses. In the case of areas *d* and *d'*, transfer port 9 comprises sections cut out of the cylinder wall and the flange 5 opposite the exhaust port 6 and the intake port 11, the latter being shown only in Figure 1. The mass of metal removed in forming port 9 is substantially equal in amount to that removed in forming both exhaust port 6 and intake port 11. Since the masses of metal in approximately opposite areas of the cylinder are everywhere equal, there is no possibility of heat distortion caused by unsymmetrical distribution of metal.

The operation of the engine is as follows:

When piston 12 is near its uppermost position, intake port 11 will be open and at that time the 15 space in crank case 8 will be at sub-atmospheric pressure and a charge will be drawn in. Shortly after piston 12 starts its downward travel the skirt of piston 12 will close intake port 11, and the mixture of gases in crank case 8 will be 20 partially compressed. Near the lowermost position of piston 12, exhaust port 6 will begin to open and as the piston moves farther downward, transfer port 9 will be uncovered, admitting the compressed mixture from crank case 25 8 to cylinder 1. This mixture enters the cylinder at a high rate of speed and is directed upwardly along the side of the cylinder by baffle 14 which forms a part of the piston head. Scavenging of the burnt gases will take place as the 30 piston starts its upward travel and as the fresh charge enters. The upstroke of piston 12 will compress the gas in cylinder 1. The charge will be fired by a conventional ignition system when the piston is in its uppermost or firing position, 35 and this firing will drive the piston downward to start another cycle.

It will be obvious from the above description that I have produced an engine of simplicity and efficiency, free from bolted, welded or brazed 40 manifolds or the like, and capable of production in miniature without the failures and defects of prior art engines of this class. While the invention has been described as embodied in a miniature engine to which it is especially 45 applicable, it is to be understood that the novel features may be applied to an engine of any size and that while I have shown and described only one specific embodiment, it is obvious the invention may take other forms within the scope 50 of the claims without departing from the spirit and scope of my invention.

What is claimed is:

1. An internal combustion engine of the crank case compression type, including a cylinder with 55 exhaust ports and a piston enclosing a working space; a crank case communicating with said working space through a transfer port in the cylinder and controlled by the piston; a crank and a connecting rod, the parts being so constructed and arranged that the cylinder has an external flange approximately in the plane of the lower limit of the working space, said flange resting on the crank case, the transfer ports being formed in the lower face of the flange and the exhaust ports being adjacent the upper face of the flange.

2. An internal combustion engine of the crank case compression type, comprising a crank case having a cylinder supporting portion thereon, 70 said portion having an inlet passage to said crank case and a transfer passage; a cylinder having a peripheral mounting flange resting upon said portion with a substantial portion of said cylinder depending within said portion, said 75

5 cylinder having a transfer port on the lower side of said flange connected to said transfer passage and an exhaust port on the upper side of said flange, said ports being substantially coaxially related; and a piston movable in said cylinder and enclosing the working space therein.

10 3. An internal combustion engine of the crank case compression type, comprising a crank case having a cylinder supporting extension thereon, said extension having an inlet passage to said crank case and a transfer passage; a cylinder having a peripheral mounting flange resting upon said extension with a substantial portion 15 of said cylinder depending within said extension, said cylinder containing a plurality of transfer ports below said flange and communicating with said transfer passage and a plurality of exhaust ports above said flange, said exhaust ports being substantially coaxially related to corresponding ones of said transfer ports; and a piston movable in said cylinder and enclosing the working space therein.

20 4. An internal combustion engine of the two-cycle type comprising a crank case including an open-ended extension having an inlet port and

25 a transfer passage; a cylinder having a peripheral mounting flange resting on said extension with a substantial portion of the cylinder depending within said extension, said cylinder containing at least one transfer port formed in the bottom face of said flange and inclined to the axis of the cylinder, said port connecting said cylinder to said transfer passage, and said cylinder having at least one exhaust port formed therein at the upper face of said flange and substantially coaxial with said transfer port; and a piston with a baffle thereon movable in said cylinder.

30 5. In an internal combustion engine a crank case having a cylinder supporting extension; a cylinder carried by said extension and having a skirt projecting within said extension; and a mounting flange on the cylinder substantially midway between the cylinder ends and resting on said crank case extension, said cylinder having an exhaust port above the flange in a position 35 to be isolated from the crank case by said flange, and a transfer port at the lower face of said flange inclined to the cylinder axis and substantially coaxially related to the exhaust port. 25
